US00D811388S

(12) **United States Design Patent** (10) **Patent No.:** **US D811,388 S**
(45) **Date of Patent:** **** Feb. 27, 2018**

(54) **WEARABLE ELECTRONIC DEVICE**

(71) Applicant: **Samsung Electronics Co., Ltd.**, Suwon-si (KR)

(72) Inventor: **Alex Rochat**, Seoul (KR)

(73) Assignee: **SAMSUNG ELECTRONICS CO., LTD.**, Suwon-si (KR)

(**) Term: **15 Years**

(21) Appl. No.: **29/541,387**

(22) Filed: **Oct. 2, 2015**

(30) **Foreign Application Priority Data**

Apr. 8, 2015 (KR) 30-2015-0017849

(51) **LOC (11) Cl.** **14-02**

(52) **U.S. Cl.**

USPC **D14/344**

CLAIM

The ornamental design for a wearable electronic device, as shown and described.

DESCRIPTION

FIG. 1 is a front perspective view of a wearable electronic device showing my new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines depict portions of the wearable electronic device that form no part of the claimed design.

1 Claim, 7 Drawing Sheets
